UNITED STATES PATENT OFFICE.

AUGUST M. H. DE BRUYCKER, OF NEW YORK, N. Y.

PADLOCK.

957,033.

Specification of Letters Patent.

Patented May 3, 1910.

Application filed July 17, 1909. Serial No. 508,155.

To all whom it may concern:

Be it known that I, AUGUST M. H. DE BRUYCKER, a citizen of the United States, and a resident of the city of New York, borough of Brooklyn, in the county of Kings and State of New York, have invented a new and Improved Padlock, of which the following is a full, clear, and exact description.

- 10 The invention relates to locks having a main bolt formed of hook members, such, for instance, as shown and described in the Letters Patent of the United States, No. 917,536, granted to me April 6, 1909.
- 15 The object of the invention is to provide a new and improved padlock, having both side arms of the hasp notched for engagement by the hooked members of a bolt, actuated by key-controlled means.
- 20 A practical embodiment of the invention is represented in the accompanying drawings forming a part of this specification, in which similar characters of reference indicate corresponding parts in all the views.
- 25 Figure 1 is a sectional side elevation of the padlock and showing the hasp in locked position; Fig. 2 is a like view of the same, showing the hasp unlocked and in open position; Fig. 3 is a cross section of the same 30 on the line 3—3 of Fig. 1; and Fig. 4 is a side elevation of one of the tumblers.
- The padlock casing A is provided near its sides with recesses B, B', for engagement by side members C', C² of the hasp C. The side members C', C² of the hasp are provided at their inner faces with oppositely-disposed notches C³, C⁴, adapted to be engaged by the hooks D², D³ of the members D and D' of the lock bolt, and which members D, D' are pivoted on a pivot E, preferably in the form of a stud secured to the lock casing A. The bolt members D and D' are pressed apart by a spring F, seated at its ends in suitable recesses formed 45 near the outer hook ends of the bolt members D and D', the spring F serving to normally hold the hooks D² and D³ in engagement with the notches C³, C⁴. The members D and D' of the bolt are caused to 50 swing by the use of one or more tumblers G, controlled by a key H and preferably mounted in a tumbler casing I secured to the bolt casing A, as indicated in Fig. 3. The

tumblers G when in the position shown in Fig. 1 extend lengthwise of the padlock, 55 between the inner ends of the bolt members D and D', so that the spring F can hold the members D and D' apart, so that the hooks D², D³ engage the notches C³, C⁴ of the hasp C, thus holding the latter in a closed 60 position. Now when the key H is inserted and turned, to turn the tumblers G, then the latter act on the inner ends of the bolt members D, D' to impart a swinging motion to the same, so that the hooks D², D³ 65 move out of engagement with the notches C³, C⁴, thus unlocking the hasp C and allowing opening thereof, as indicated in Fig. 2.

In order to withdraw the key H, the 70 tumblers G have to be turned back to the lengthwise position shown in Fig. 1, and when this takes place the spring F opens the bolt members D, D', so that the hooks D², D³ thereof readily engage the notches 75 C³, C⁴ whenever the hasp C is pushed back into locking position.

The side arm C' of the hasp C is provided with the usual flattened portion C⁵ and the annular groove C⁶, adapted to be engaged 80 by a pin J, so as to allow of sliding the hasp C outward or inward and to allow of turning the hasp with the side arm C' as the fulcrum, whenever the hasp is in the open position shown in Fig. 2, to readily engage 85 the hasp with the parts to be locked.

The padlock shown and described is very simple and durable in construction, and as the bolt members engage both side arms C', C² of the hasp, it is evident that the hasp is 90 securely held in position to prevent withdrawal of the hasp C unless both bolt members are actuated simultaneously by the tumblers G controlled by the proper key H.

Having thus described my invention, I 95 claim as new and desire to secure by Letters Patent:

A padlock comprising a hasp having its side arms provided with notches on their inner faces, a bolt comprising pivotally connected members having at one end outwardly extending hooks for engaging the notches, a spring between the members at the said end, a tumbler case secured between the members at the opposite end from the 105 spring, and key controlled tumblers in the

said casing for moving said members against the tension of the spring whereby to disengage the hooks from the notches, and a casing having sockets for receiving the arms of the hasp, and a cavity for the bolt and openings between the cavity and the sockets for the passage of the hooks.

In testimony whereof I have signed my name to this specification in the presence of two subscribing witnesses.

AUGUST M. H. DE BRUYCKER.
